(57) **CLAIM**

The ornamental design for a battery cap retention assembly, as shown and described.

DESCRIPTION

FIG. 1 is a front perspective view of a battery cap retention assembly according to this disclosure;

FIG. 2 is a back perspective view of the battery cap retention assembly according to this disclosure;

FIG. 3 is an exploded view of the battery cap retention assembly according to this disclosure;

FIG. 4 is a front view of a portion of the battery cap retention assembly according to this disclosure;

FIG. 5 is an enlarged view of a portion of FIG. 4 according to this disclosure;

FIG. 6 is a front view of a device with the battery cap retention assembly according to this disclosure;

FIG. 7 is a perspective view of the device with the battery cap retention assembly in a closed state according to this disclosure; and,

FIG. 8 is a perspective view of the device with the battery cap retention assembly in an opened state according to this disclosure.

Broken lines in the drawings show environmental structures or boundaries that form no part of the design to be patented.
